CLAIM

The ornamental design for a control knob for kitchen appliances, as shown and described.

DESCRIPTION

FIG. 1 is a perspective view of one embodiment of a control knob for kitchen appliances according to the present invention;

FIG. 2 is a front view thereof;

FIG. 3 is a first side view thereof, the other side being identical;

FIG. 4 is a top view;

FIG. 5 is a bottom view opposite the top view;

FIG. 6 is a bottom view of the control knob of FIG. 1 and being located on a kitchen appliance shown in broken line for context; and,

FIG. 7 is a perspective view of the control knob of FIG. 1 and being located on a kitchen appliance shown in broken line for context.

The broken lines shown in the drawings represent unclaimed portions and form no part of the claimed design.

1 Claim, 6 Drawing Sheets
